UNITED STATES PATENT OFFICE

144,973

DESIGN FOR A LADY'S SUIT

Samuel Kuznetz, New York, N. Y.

Application January 16, 1946, Serial No. 125,608

Term of patent 3½ years

(Cl. D3—4)

To all whom it may concern:

Be it known that I, Samuel Kuznetz, a citizen of the United States, and a resident of the city of New York, in the county of Kings and State of New York, have invented a new, original, and ornamental Design for a Lady's Suit, of which the following is a specification, reference being had to the accompanying drawing, forming a part thereof.

Fig. 1 is a front view of the lady's suit showing my design.

Fig. 2 is a rear view of the lady's suit shown in Fig. 1.

I claim:

The ornamental design for a lady's suit, substantially as shown.

SAMUEL KUZNETZ.
